(57) **CLAIM**

The ornamental design for a pole holding device, as shown and described.

DESCRIPTION

FIG. 1 is a perspective view of a pole holding device showing my new design;

FIG. 2 is an enlarged perspective view of the encircled area shown in FIG. 1;

FIG. 3 is a right-side view thereof;

FIG. 4 is a top view thereof;

FIG. 5 is a left-side view thereof;

FIG. 6 is a bottom view thereof;

FIG. 7 is a back view thereof; and,

FIG. 8 is a front view thereof.

In the drawings, the broken lines depict a truck and a pole and form no part of the claimed design.
